EUGENE P. BACHMANN AND WILLY H. LASCH, OF PHILADELPHIA, PENNSYLVANIA,
ASSIGNORS, BY MESNE ASSIGNMENTS, TO THE ATWOOD MACHINE COMPANY, OF
JERSEY CITY, NEW JERSEY, A CORPORATION OF NEW JERSEY

METHOD AND APPARATUS FOR TREATING OR MOISTENING YARN

Application filed June 27, 1930. Serial No. 464,362.

A principal object of this invention is to provide novel and improved apparatus for preparing or conditioning yarn, and particularly silk, for knitting or like operations.

More particularly, an object of the invention is to provide novel apparatus for effecting a closely controlled treatment of the yarn with a liquid medium, such as water, oil, or chemical, preparatory to the use of the 10 yarn in a knitting or like operation.

Another object of the invention is to provide a novel apparatus and method for conditioning yarn whereby the conditioning operation is materially facilitated, with a consequent saving in time and expense.

To this latter end, the invention contemplates provision of a novel method and apparatus for treating yarn on bobbins with a liquid conditioning medium affording an accurately gaged and graded impregnation from the inner to the outer layers of the yarn, whereby if desired the latter may be used immediately in the knitting or other operation for which it has been prepared, the yarn 25 as it passes from the bobbin to the needles showing a predetermined and substantially uniform moisture condition which is substantially maintained throughout the entire length of yarn wound upon the bobbin.

Still another object of the invention is to provide apparatus for treating yarn in bobbins with a liquid conditioning medium wherein a plurality of bobbins may be simultaneously treated.

The invention further resides in certain novel mechanical and structural features hereinafter set forth and illustrated in the attached drawings, in which:

Figure 1 is a front elevational view of a 40 machine made in accordance with our invention;

Fig. 2 is a side elevational view of a section of the machine, and

Fig. 3 is an enlarged sectional view illustrating a detail of the mechanism.

In the knitting of silk fabrics, it is essential, for best results, that the silk passing to the needles shall be in a predetermined uniformly moist condition. It is also essential 50 that the moisture content of the silk shall

not exceed an allowable maximum. Where a bobbin of yarn is uniformly moist throughout, the moisture or a substantial portion thereof will frequently have evaporated from the inner layers by the time these layers are fed to the needles, so that in practice a uniformly moistened bobbin frequently fails to afford a uniformly conditioned yarn at the needles. Considerable difficulty has been experienced in obtaining a proper condition in 60 the yarn, and those of the prior methods affording best results have involved long and expensive operations, such for example as that known as "back winding". The less expensive methods of the prior art have been 65 without exception unsatisfactory.

We have discovered a method and have provided an apparatus whereby yarn in bobbins may be rapidly treated with a liquid conditioning agent so as to render the yarn immediately available for a knitting or other operation in which it is required that the 70 yarn be delivered continuously from the bobbin in a substantially uniform and accurately regulated moisture condition.

In accordance with our invention, water or other liquid medium is applied to the yarn from the interior of a perforated bobbin or spool upon which the yarn is wound, the liquid being fed to the bobbins at a predetermined regulated pressure which is maintained until the moisture has penetrated to the outer surface of the yarn body, and is then immediately relieved. By employing a pressure sufficiently high to effect a rapid penetration 85 of the yarn, not only is there effected a considerable saving in time and expense, but the conditioning operation is highly efficient and affords an accurately graded moisture condition throughout the yarn body, the outer surface layers of the yarn being in condition for immediate employment in the production for example of a knitted fabric and the underlying layers containing a progressively greater moisture content which is not excessive even 95 in innermost layer. As a result of this process, we have found it possible to transfer the bobbins from the moistening apparatus directly to the knitting machines, with a resultant production of a highly uniform prod- 100

uct, since while the inner layers of the yarn on the bobbin contain more moisture than the exterior layers, this moisture evaporates at a rate corresponding substantially with the rate at which the yarn is fed to the needles whereby the yarn at the needles has a substantially uniform moisture content. In the event that the yarn following the conditioning treatment is not required for immediate use, it may be placed in a humidifying chamber and kept there indefinitely under the usual humidity conditions without material change in the moisture condition of the yarn as produced in the conditioning operation described above.

It is important that the liquid pressure be carefully regulated, since a too-low pressure tends to result in an over-treatment or excess moisture condition in the inner layers of the yarn, while too high a pressure renders control difficult. An over-treatment or excessive moistening of the inner layers may result in injury to the yarn and a tendency of the yarn to swell and to leave the cone. For moistening silk on a standard 6" cone which contains approximately fifty perforations ranging in size from $\frac{1}{4}$ " to $\frac{1}{8}$ " and upon which the silk is wound to approximately $\frac{3}{4}$ " in depth, we have found a water pressure of approximately ten pounds to afford highly satisfactory results, although this pressure may vary to some extent either way. In the above instance, we have found the conditioning operation for the individual cone to require approximately four seconds. The liquid pressure, of course, may be varied to suit the character of the particular yarn under treatment, the size of the perforations in the cone and the thickness to which the yarn is wound thereon, and also to some extent the composition of the treating medium.

While the apparatus employed in the practice of the method outlined above may vary widely as to form, we have obtained highly desirable results from the embodiment illustrated in the attached drawings. With reference thereto, the machine may comprise a base or frame structure 1 supporting spaced brackets 2 which in turn constitute supports for a pair of pipe mains 3 and 4. Extending upwardly from the pipes 3 and 4 at spaced intervals throughout the lengths of the latter are sleeves 5 in which are slidably fitted hollow valve stems 6, these stems having perforations 7 adjacent their lower ends and a flanged head portion 8 which when the stem is elevated as illustrated in the drawings bears against a gasket 9, which latter is thus confined between the said head portion and the lower end of the sleeve 5. In this position of the stem 6, therefore, the interior of the stem is sealed from the interior of the pipe 3 or 4, as the case may be.

Carried by the upper end of the stem 6 is a member 11 between which and the upper

end of the sleeve 5 is confined a spring 12 which functions to hold the stem in the normal elevated position as illustrated. The head 11 carries an annular rubber gasket 13 which constitutes a seat for the lower end 70 of a perforated bobbin 14 upon which the silk thread is wound in the usual manner. The bobbin is perforated only in that part which is covered by the silk yarn. The sleeve 5 also carries an annular gasket 10 which, 75 when the member 11 is depressed, as herein-after set forth, is engaged by the lower edge of the said member to form a seal around the outside of the stem 6 above the sleeve.

Extending upwardly from the base frame 1 are side standards or uprights 15. These standards carry transversely projecting arms 16 which extend inwardly to a point directly overlying the bobbins 14 seated on the rubber gaskets 13. Pivotedly supported on the standards 15 are arms 17 which also extend inwardly to a point overlying the inner ends of the arms 16, and depending from each of the arms 17 is a stem 18 which extends downwardly through apertures in the inner ends 90 of the arms 16 and at their lower ends carry socket elements 19 which are adapted to engage the tops of the bobbins 14 as illustrated in Fig. 1. Springs 21 surround these rods 18 and exert a pressure tending to maintain 95 the arms 17 in an elevated position in which the socket elements 19 are held clear of the tops of the bobbins 14. Supported on the tops of the arms 17 and preferably extending the full length of the machine are rods 22 100 which may be pivotally secured to the standards 15 by means of arms 23. These rods 22 are engaged from above by a yoke 24 from which depend actuating rods 25 by means of which these yokes may be drawn downwardly 105 to thereby exert pressure on the rods 22 sufficient to depress the arms 17 on their pivots against the tension of the springs 21. The rods 25 may be connected to a treadle or to any suitable means for applying manual or 110 other force for depressing the yoke. The yoke, therefore, and associated parts constitute a means whereby the socket elements 19 may be brought down upon the tops of the bobbins 14 to force the latter firmly on their 115 seats 13 and to retain them in that position. In operation, the wound bobbins are placed upon the seats 13 and the yoke thereupon depressed to bring the socket members 19 into engagement with the bobbin tops. This pressure not only forces the bobbin to its seat upon the gaskets 13 but also depresses the member 11 and the hollow valve stem 6 against the pressure of the spring 12, this depression continuing until the apertures 7 120 clear the lower end of the sleeve 5 and are in communication with the interior of the pipe 3 or 4, as the case may be, and until the lower edge of the member 11 meets the gasket 10. The pipes 3 and 4 are in communication with 125 130

a suitable source of water under predetermined pressure, which water is accordingly forced through the hollow stem 6 and jet nozzle 20 to the interior of the bobbins 14. After filling the bobbins, the water forces its way outwardly through the perforations in the bobbin and into the body of wound silk and eventually appears in minute beads at the surface of the silk body. As soon as these surface beads appear, indicating that the water has passed completely through the mass of silk, the yoke 24 is released, permitting the depressed parts to elevate and thereby shutting off the supply of water to the bobbins. The bobbins may then be removed and replaced.

It will be apparent that the machine may be operated to less than full capacity if desired without loss of pressure, since the valves to the respective bobbin heads are opened entirely by pressure exerted through the bobbins themselves, so that to those heads not containing bobbins no water is admitted.

It will be understood that the invention is not restricted to the treatment of silk with water, and may be employed in principle and to advantage for the conditioning or treatment of any type of yarn on bobbins or their equivalent with any character of liquid medium. It will further be understood that there may be considerable modification in the apparatus as herein disclosed without departure from the invention.

We claim:

1. The method of conditioning yarn, which consists in winding the yarn upon a hollow perforated bobbin, applying fluid pressure to the interior of the bobbin, and discontinuing said fluid pressure immediately subsequent to the appearance of moisture at the outer surface of the wound yarn.

2. The method of conditioning yarn, which consists in winding the yarn upon a hollow perforated bobbin, and applying liquid to the interior of the bobbin under a pressure controlled and regulated to afford a predetermined condition in the inner layers of yarn when the liquid appears on the outer surface.

3. The method of conditioning yarn, which consists in winding the yarn upon a hollow perforated bobbin, causing a liquid treating medium to penetrate the wound mass of yarn from the interior of the bobbin outwardly, regulating the pressure on said liquid to determine the time required for said penetration, and discontinuing the treatment subsequent to complete penetration of said mass.

4. In apparatus for treatment of yarn, the combination of a pipe adapted for connection with a source of liquid under pressure, bobbin supports having connection with the interior of said pipe, valve means controlling said connection, and means operated by pressure on said bobbin for opening the valve.

5. In apparatus for treatment of yarn, the combination with a manifold adapted for connection with a source of fluid under pressure, of a plurality of bobbin supports having passages communicating with said manifold, means for retaining hollow perforated bobbins on said supports with their interiors in communication with said passages, and means for controlling passage of fluid to the bobbins.

6. In apparatus for treatment of yarn, the combination with a duct adapted for connection with a source of liquid under pressure, of a bobbin support having a port whereby communication may be established between the said duct and the interior of the bobbin, a valve controlling the connection between the duct and the said port, said valve including a stem upon which said support is mounted, a spring normally retaining said stem in valve-closing position, and means for exerting a pressure through a spindle seated on said support to open the valve against the pressure of said spring.

7. In apparatus for treatment of yarn, the combination with a duct adapted for connection with a source of liquid under pressure, said duct having a port, of a hollow valve stem slidably mounted in said port and adapted to close the latter, said stem being adjustable to a position effecting a communication between the interior of the duct and the interior of the stem, a spindle support carried by said stem and having an opening communicating with the interior of said stem and through which communication is established between the interior of the stem and the interior of a spindle seated on said support, means whereby the stem is normally maintained in the valve-closing position, and means for shifting said stem to effect communication between the said duct and the interior of the spindle.

8. In apparatus for treatment of yarn, the combination with a plurality of bobbin supports each having an opening communicating with the interior of a bobbin seated on the support, a fluid pressure duct, and a valve controlling the connection between the said duct and each of said bobbin support openings, means for normally maintaining said valves closed, and means whereby said valves are opened by pressure exerted through the said bobbins.

9. In apparatus for treatment of yarn, the combination with a pressure duct, of a plurality of bobbin supports associated with said duct and each having a port, valve-controlled means for establishing communication between the duct and said ports, a member overlying and adapted to engage the tops of bobbins seated on the supports, means for depressing said member to exert a downward pressure upon the bobbins and through the bobbins upon said supports, and mechanism

operatively connecting the supports and the
said valves whereby said downward pres-
sure effects an opening of the valves estab-
lishing communication through the said ports
5 between the duct and the interior of said
bobbins.
